UNITED STATES PATENT OFFICE

FRED W. TAMKE AND GEORGE WILLIAM BOH, OF NEW ORLEANS, LOUISIANA, SAID
TAMKE ASSIGNOR TO SAID BOH

BOX OR CONTAINER

Application filed July 11, 1928. Serial No. 292,005.

This invention relates to a box or container.

An object of the invention is the provision of a box or container formed of cardboard and composed of three main parts 5 which are joined together in a complete unitary structure by metal staples or some other well known form of fastening means.

A further object of the invention is the 10 provision of a box or container formed of cardboard or other suitable material and having flanges projecting from the sides and ends of the box which operate as a protective means against damage resulting from 15 dropping the box or from blows against the surface during handling.

This invention will be best understood 20 from a consideration of the following detailed description in connection with the accompanying drawings; nevertheless, it is to be understood that the invention is not confined to the disclosure being susceptible of such changes and modifications as shall define no material departure from the salient 25 features of the invention as expressed in the appended claim.

In the drawings:—

Figure 1 is a view in perspective of a box 30 or container constructed according to the principles of my invention,

Figure 2 is a longitudinal vertical section taken along the line 2—2 of Fig. 1,

Figure 3 is a horizontal section taken along the line 3—3 of Fig. 1,

Figure 4 is a plan view of a blank from 35 which the side walls are formed.

Referring more particularly to the drawings, 10 designates a body member which is of sufficient size to provide laterally projecting flanges 11 at the bottom forming all bottom edges of the box when completed. A top member 12 is co-extensive with the body member 10 and is of sufficient size to provide lateral extensions or flanges 13 projecting 40 from all four upper edges of the box.

The side walls 20 and 21 of the box or container are connected together by an end wall 22 and by means of flaps 23 and 24. A second end wall 25 is connected by means of a 45 flap 26 to the side wall 21.

The dotted lines 28 indicate indentations or scoring of the material whereby the flaps 23, 24, 26 and 29 may be bent for the formation of the side and end walls of the body 55 of the box.

The sections 20 and 21 have lateral extensions 31 and 32 and the material between the sections and the extensions is indented or creased as indicated at 33. The sections 22 and 25 have lateral extensions 35 and 36 providing flanges, and the material between the sections and the extensions or flanges is indented or creased as indicated at 37 to provide for the bending of the flanges horizontally and at right angles to the sections. 60

In order to construct the box, the body of which includes the section 20 is placed in a vertical position, as shown in Fig. 3, and the connection 23 is bent at 28 inwardly in flat contact with the inner face of an end of the section 20 and then bent at right angles to form the side wall from the section 22. The connection 24 is bent in flat contact with the adjacent connected end of the sections 21, while the connection 26 is bent in flat contact with the adjacent connected end of the 65 end wall or sections 21, while the flap 29 is bent in flat contact with the free end of the section or end wall 20. Staples 40 are employed for securing the connections 23, 24 and 26 to the adjacent ends of the respective side and end walls, while staples 43 secure the flap 29 to the free end of the end wall 20, thereby forming the chamber 42.

The flanges or extensions 32 and 36 of the sections are secured respectively by means of staples 44 to the extensions 11 of the bottom or base member 10. The flanges 31 and 35 of the side and end walls are secured to the extensions 13 of the top 12 by 70 means of staples 45.

It will be seen by the above construction that a box or container is provided having laterally projecting edges which will absorb shock and blows and thus protect the contents of the container from injury during treatment and handling. These edges are sufficiently extended to normally maintain the side and end walls of the box out of engagement with the surface of other boxes and 75 100

will also aid in preventing the breakage of the side and end walls.

We claim:—

5 A container comprising a rectangular body member and top and bottom members, the body member having side and end walls, said walls having flanges at their upper and lower edges projecting horizontally outwardly therefrom, the top and bottom members having extending portions co-extensive with said flanges, and adapted to be secured thereto, said side and end walls being formed from a single strip of material, the end walls being formed by folding a portion of the material back upon the side walls into coincidence with portions thereof and then away from said side walls to provide two ply corner extensions which underlie and overlie the top and bottom members respectively, and extend to the edges thereof, and staples for 10 fastening the associated flanges and extensions to maintain the container in set-up condition.
